LOCK

Vincent E. Malley, Terryville, Conn., assignor to
 Eagle Lock Co., New York, N. Y., a corporation
 of Connecticut

Application April 29, 1937, Serial No. 139,749

2 Claims. (Cl. 70—20)

The present invention relates to locks and has special reference to small padlocks for use on the pockets of garments.

The principal object of the invention is to provide a padlock of the character indicated which is simple in construction and convenient in use and the trouble involved in the possible loss of a key is avoided.

The preferred embodiment of the invention is illustrated in the accompanying drawing, in which,

Figure 1 is a longitudinal sectional elevation of the lock;

Fig. 2 is a sectional view taken on the line 2—2 of Fig. 1;

Fig. 3 is a view similar to Fig. 1, but with the parts shown in unlocked position; and

Fig. 4 is a sectional view taken on the line 4—4 of Fig. 1.

20 My improved lock as illustrated in the drawing, is in the form of a padlock having a lock-case 2, a sliding shackle 4, a lock-bolt 6, and the usual coil spring 7 for moving the shackle outwardly when the bolt releases the shackle. The lock-bolt is mounted to slide in a guideway formed by a U-shaped portion 8 of a bracket plate 10 that is secured to one side of the lock-case. The lock-bolt is adapted to be moved into locking engagement in a notch 12 in the heel of the shackle 30 when the shackle is moved into the lock-case.

In accordance with the present invention, the lock-bolt is adapted to be moved into and out of locking engagement with the shackle by means of a lever 14 which is pivotally mounted on a stud or pin 16 secured to the bracket plate 10. The lever 14 has its upper end extending through a clearance slot 18 in the underside of the U-shaped portion 8 and into an aperture 20 in the lock-bolt. The lever 14 is turned in a direction to slide the lock-bolt into locking engagement in the notch 12 by means of a spring 22 coiled about the pivot pin 16 and having one end engaging the rear side of the upper arm of the lever, the spring being held under tension by the engagement of its other end with the lower wall of the lock-case.

The other arm of the lever 14 extends through a clearance slot 24 in the bottom wall of the lock-case, and is formed with a projecting finger-piece 26.

With this construction, upon the shackle being moved into the lock-case, the spring 22 through the lever 14 slides the bolt 6 into locking engagement with the shackle. When it is desired to unlock the shackle, the user moves the finger-piece 26 to turn the lever 14 in a direction to retract the lock-bolt.

It will be apparent that my improved lock is particularly adapted to be used on garments where a secure fastening for the pocket is required. The device affords all the security that is required when used on a garment and the trouble involved in the possible loss of the key is avoided.

As will be evident to those skilled in the art, my invention permits various modifications without departing from the spirit thereof or the scope of the appended claims.

What I claim is:

1. In a lock of the class described, the combination of a lock-case, a shackle, a bolt mounted in the lock-case adapted to be moved into and out of locking engagement with the shackle, and a device pivoted in the lock-case having one end operatively connected with said bolt and adapted to be turned in opposite directions to move the bolt into and out of locking engagement with the shackle, said device having a finger-piece on its other end projecting outside of the casing for turning said device to move the bolt out of engagement with the shackle.

2. In a lock of the class described, the combination of a lock-case, a shackle, a bolt adapted to be moved into locking engagement with the shackle when the shackle is moved into the lock-case and to be moved out of locking engagement with the shackle, a device comprising a lever pivoted within the lock-case and having one end operatively connected with the lock-bolt whereby upon turning said device in opposite directions the lock-bolt may be moved into and out of locking engagement with the shackle, and a spring for turning said device in a direction to move the lock-bolt into locking engagement with the shackle, said lever having its other end provided with a finger-operable piece projecting outside of the lock-case for turning said device in the opposite direction.

VINCENT E. MALLEY.
